ABSTRACT OF THE DISCLOSURE

A pattern reproducing device which changes only the height of copied matter without distortion of other dimensions by selection of critical ratios of length of particular pantographic arms actuating a pattern follower and reproducer.

The object of the invention is to provide a device for reproduction of patterns, such as letters of the alphabet, with variation of comparative dimensions and/or of relative angles of portions of the pattern.

According to the present invention, a pattern-reproducing device comprises a linear guide member, a support movable along the guide member, a first element mounted on the support and rotatable about a first axis normal to a plane containing the line of movement of the support, said first element having a point of connection respectively for a copying tool or a pattern-follower tool at a radius from said first axis, a second element mounted on the support and rotatable about a second axis normal to said plane, said first and second axes being spaced in said plane both along the direction of movement of the support and normal thereto, said second element having a point of connection respectively for a pattern-follower tool or a copying tool at a radius from said second axis, and a coupling member pivotably connected to the first element and to the second element.

Two embodiments of the device are shown in the accompanying drawings, wherein:

FIG. 1 is a diagram to show the principle of the device with simple levers;

FIG. 2 is a diagram to explain the operation of a device with two-arm levers;

FIG. 3 is a plan view of the device;

FIG. 4 is a perspective view of a similar device, with a pattern and an engraving machine;

FIGS. 5 and 6 are plan views, on a smaller scale, to show respectively horizontal and vertical increase of a dimension of the pattern;

FIGS. 7 and 8 are plan views, on a similar scale, to show respectively anti-clockwise and clockwise deformation of a pattern.

Referring to FIG. 1, the line $x-x'$ is the axis of transverse movement of a support S along a guide (not shown). On the support S a first element $O'P$ is pivotable about a first axis O' , and a second element OQR is pivotable about a second axis O . The point P of the first element is connected to the point Q of the second element by a coupling member PQ . A pattern-follower tool is mounted at point R , to be moved over a pattern in the shape of a letter "E," and a tracing tool is mounted at point P to copy the pattern. If it is desired to reproduce the copy with the vertical lines only two-thirds of the height of the corresponding vertical lines of the pattern, the ratio of the lengths OR to OQ is made as three to two, and the ratio of the lengths OQ to $O'P$ is also made as three to two.

In FIG. 2 a carriage G is movable along a guide rail xx' . An arm ABC is pivoted at B on a rigid arm H fixed to the carriage G , so that the lengths AB/BC represent

2

the desired ratio of the respective heights of a pattern and of a resultant copy. An arm FED is pivoted at E on a rigid arm J fixed to the carriage G and the lengths FE and ED are equal, whilst the lengths BC and ED have the same desired ratio mentioned above.

5 A coupling arm CD is pivoted at C on the arm ABC and at D on the arm FED . When the pattern follower tool at A is at mid-height of the pattern, in the shape of a letter "E," the arms ABC and FED are substantially parallel to the rail xx' , and the coupling arm CD is substantially perpendicular to the arms ABC and FED .

10 When the tool at A is caused to follow the pattern, the horizontal strokes made by the copying tool at F are of the same length, whereas the vertical strokes are reduced by the ratio ED divided by BC . If the pattern-follower tool is placed at F and the copying tool at A , then the inverse ratio is obtained.

15 In practice, the device introduces a curvature into the vertical line reproduced, but the degree of curvature is negligible.

20 FIG. 3 shows the device having a cylindrical guide rail 1 fixed on a base (not shown). A carriage 2 is mounted movably on the rail 1 by supporting rollers 3 and 7, and lateral guiding rollers 4, 5 and 6, the roller 6 being adjustable by means of an eccentric, for taking up play. Arms 8 and 11 are secured rigidly to the carriage 2 by means of respective finger nuts 10 in slot 9 and 13 in slot 12. A slide 17 is pivoted at 18 on the arm 8 and receives slidably an arm 14 which can be locked by a screw 33 in a slot 16. The arm 14 receives at 15 a pattern-follower tool such as a needle. Arm 14 is pivoted at 31 to a slide 19 in which a transverse coupling bar 20 can be locked by a finger nut 22 in slot 21. The bar 20 is pivoted at 30 on a slide 28 securable to an arm 23 by a finger nut 29 in a slot 25. A slide 26 is pivoted at 32 on the arm 11, and receives slidably the arm 23 securable by a finger nut 27. The arm 23 carries the tracer tool such as a graving instrument, at 24, or is coupled at 24 to a pantograph or other control device for an engraving machine. Finger nuts 10, 13 and 22 can be released to permit adjustment of the separation of the arms 14 and 23 with respect to each other and the rail 1.

25 40 45 Screw 33 and finger nut 277 can be released to permit adjustment of the slides 17 and 26 along their respective arms, for altering the reproduction ratio.

FIG. 4 shows a similar device in perspective, the pattern-follower tool 15a being moved along the subject letter "A," and instead of a tracer tool the point 24a is connected through a linkage L, which might be a pantograph (not shown), to a graving machine tool T.

50 55 FIG. 5 illustrates reduction of height of a subject letter "E" whilst keeping the width the same. FIG. 6 illustrates inversion of the device to permit increase of the height of a subject letter "A" whilst keeping the width the same.

FIGS. 7 and 8 show that, if the device is set up with the transverse coupling bar 20 not initially at a right angle to the rail 1, the resultant letter "M" is deformed anti-clockwise (FIG. 7), or clockwise (FIG. 8).

60 The device may be constructed in mirror-image manner if it is desired to position it to the right-hand side of the pattern, instead of to the left-hand side as shown in FIGS. 4 and 5.

I claim:

- 65 1. In a pattern reproducing device comprising:
(a) a linear guide member;
(b) a support movable along said guide member;
(c) a first element mounted on said support and rotatable about a first axis normal to a plane containing the line of movement of said support, said first element having a point of connection respectively for a copying tool or for a pattern follower tool at a radius from said first axis;

- (d) a second element mounted on said support and rotatable about a second axis normal to said plane, said first and second axes being spaced in said plane both along the direction of movement of said support and normal thereto, said second element having a point of connection respectively for a pattern follower tool or for a copying tool at a radius from said second axis; and
- (e) a coupling member connected by a first fixed pivot means to the first element and connected by a second fixed pivot means to the second element, wherein the line joining the points of pivotal connection of said coupling is normal to the line of movement of said support when the said first and second elements are parallel to the line of movement of said support; the improvement in which the ratio of the radius of the tool point from the second axis and the

5

radius of the coupling point of the second element from the second axis is approximately equal to the ratio of the radius of the coupling point of the second element from the second axis and the radius of the tool point of the first element from the first axis.
